UNITED STATES PATENT OFFICE.

ULRICH HARDER, OF ST. LOUIS, MISSOURI.

DESIGN FOR A TAMPON-CARRIER, &c.

SPECIFICATION forming part of Design No. 26,707, dated March 2, 1897.

Application filed December 19, 1896. Serial No. 616,343. Term of patent 7 years.

To all whom it may concern:

Be it known that I, ULRICH HARDER, a citizen of the United States, residing in the city of St. Louis and State of Missouri, have invented and produced a new and original Design for Tampon-Carriers and Tongue-Depressors, of which the following is a specification.

In the accompanying drawings, which form part of this specification and wherein like symbols refer to like parts wherever they occur, Figure 1 is a front view of a device composed of a tampon-carrier and a tongue-depressor combined according to my design. Fig. 2 is a side view thereof.

The portion 1 of my design corresponding with the handle of the device is long, smooth, and straight, with a round or cylindrical section. At one end is a slightly-enlarged knob 2 with the space adjacent provided with one

or more annular depressions 3 or made rough, as indicated at 4.

At the other end 5 the side lines in one plane are gradually widened out and then curved together into a spatulate or spoon-shaped form, while the side lines in a plane at right angles to said first-mentioned plane are curved to the same side. The central portion of this spatulate end is thicker than the marginal portion, which is beveled almost to an edge. 25

What I claim is—

The design for a tampon-carrier and tongue-depressor substantially as herein shown and described. 30

ULRICH HARDER.
